SERVING TRAY

Morris B. Solomon, New York, N. Y.

Application June 18, 1936, Serial No. 85,825

1 Claim. (Cl. 65—53)

The present invention relates to improvements in a serving tray and has for an object to provide means for holding a receptacle in upright position regardless of the position of the tray frame.

Another object is to provide a tray to carry a plurality of receptacles in upright position regardless of the position of the tray frame.

A further object is to provide a tray which may be carried in any position without tilting or spilling a receptacle carried by the tray.

A still further object is to provide a tray with a frame such that it may be stood on either end or set on an inclined surface without tilting the receptacles carried by the tray.

With the foregoing and other objects in view, the invention will be more fully described hereinafter, and will be more particularly pointed out in the claim appended hereto.

In the drawings, wherein like symbols refer to like or corresponding parts throughout the several views.

Figure 1 is a top plan view of a tray made according to the present invention.

Figure 2 is a section taken on the line 2—2 of Figure 1.

Figure 3 is a section taken on the line 3—3 of Figure 1.

Figure 4 is a section taken on the line 4—4 of Figure 1.

Figure 5 is a section taken on the line 4—4 of Figure 1 showing the frame set on a tilted surface, and

Figure 6 is a side elevation of the tray showing it set on one end.

The tray forming the subject of the present invention is designed particularly for use at sea where great difficulty is experienced in carrying and serving liquids because of the rolling and pitching of the boat. In the form shown the tray is particularly applicable to the serving, for example, of cocktails or other beverages in a large container and a number of smaller individual containers. In addition to the use on boats the tray has general application wherever it may be desirable to have a carrying device which may be set at any angle and which may be carried with the minimum of care while preventing the spilling of liquids carried.

Referring now to the drawings, a pair of spaced rings 10 is provided with diametrically mounted end rails 11 which extend out beyond the circumference of the rings. At suitable points these rails are connected one to another by side pieces 12. The side pieces are attached to the end rails

11 within the circumference of the rings 10 and are spaced apart sufficiently to carry therebetween a receptacle holding frame. The receptacle holding frame is composed of a pair of sectors 13 secured to the upper portions of the side pieces 12 at approximately the mid point between the rings 10. In the sectors 13 is pivoted a ring 14 which is free to revolve about pivots 15. A second ring 16 is pivoted within ring 14 freely to revolve about an axis at right angles to the axis of the ring 14. The ring 16 is proportioned to receive, in this embodiment of the invention, a large receptacle such as the cocktail shaker 17. The size of the ring is such that the greater mass of the cocktail shaker 17 hangs below the ring so that by gravity the shaker tends to hang in a vertical position regardless of the position of the rings 10 and other frame members.

Between the outer ends of the end rails 11 are pivoted sub-frames 18 which are free to revolve about their pivots 19 on axes longitudinal of the tray. Within the sub-frames 18 at suitably spaced intervals are placed receptacle holding rings 20 pivoted to opposite sides of the sub-frames 18 so as to freely revolve about axes at right angles to the axes of the sub-frames 18. These rings 20 are adapted in the device shown to carry a service of glasses 21 and are of such a size to permit the greater mass of each glass to hang below the axes of rotation of its ring so as to tend by gravity always to hang in a vertical position. The pivots 22 of the rings 20 are placed in the side rails of the sub-frame and are attached to the rings at diametrically opposite points thus providing an attachment on the axis of balance of each ring. The end pivots 19 of each of the sub-frames 18 are likewise attached to points on the center of balance of the sub-frame. In order to prevent rolling of the rings 10 when the tray is set on a flat surface each ring is provided with a pair of spaced feet 23.

Referring particularly to Figure 3, it will be noted that the spacing of the rings 20 is such as to permit complete rotation about the pivots 22 when each ring contains a glass 21, the distance being such as to provide clearance at all points during rotation.

From the structure above described it will be seen to follow that the tray may be tilted to an angle such as shown in Figure 5 without disturbing the upright position of the vessels carried thereby. In this figure the tray is shown as set on a slanted surface, for example, a table which is rocked by the motion of a boat. In this posi-

tion the cocktail shaker ring 16 revolves about its pivots 24 while the shaker 17 itself remains upright.

5 The sub-frames 18 with the glasses 21 revolve about their end pivots 19 without moving the glasses from their upright position.

As shown in Figure 6 the tray may be set upright on the side of one of the rings 10 without disturbing the position of the glasses or cocktail 10 shaker. In this position the ring 14 revolves about its pivots 15 to permit the shaker 17 to lie longitudinally of the tray frame. Also, the 15 glasses 21 in the rings 20 have revolved about their pivots 22 so that the glasses lie in the longitudinal plane of the tray.

It will likewise be apparent from Figure 6 that the tray filled with the shaker and glasses may be carried by means of the upper ring 10. It is also possible to swing the tray while holding it 20 in this position without causing any disturbance of the contents of the various receptacles. It is impossible, therefore, to spill the contents of this tray by tilting or swinging, and in addition to this, the tray may be completely revolved about 25 a transverse axis without spilling any of the contents.

The size of the various rings as well as their 30 shape may be varied to receive various types of receptacles designed to be carried in the tray. The requirement being that they should hold the receptacle with its greater mass below the axis of rotation of the rings. Likewise the number and arrangement of the rings may be varied to suit the particular conditions.

35 The form of the end pieces of the tray is not limited to rings 10 as shown but any suitable end piece may be substituted. The rings are

shown as particularly in keeping with the modern style in this type of device.

It is obvious that various changes and modifications may be made in the details of construction and design of the above specifically described embodiment of this invention without departing from the spirit thereof, such changes and modifications being restricted only by the scope of the following claim.

What is claimed is:

A serving tray comprising a carrying frame including a pair of spaced members, each of which is provided with supporting feet, end rails supported by each of said members, a pair of bars connecting the two end rails, two freely revolving concentric rings, an upwardly extending arcuate bar carried by each of said pair of bars, the outer ring being pivotally connected with said arcuate bars and the inner ring being pivotally connected with the outer ring, said inner 20 ring being adapted to hold a container, a holder frame pivotally connected with said end rails, and a plurality of receptacle holders pivotally connected with said holder frame, whereby a container placed within the inner concentric ring 25 and receptacles placed within the receptacle holders in the holder frame will revolve freely and remain upright when the carrying frame is in any position from the vertical to the horizontal, and while the tray is supported by the supporting feet of the carrying frame, or rests upon the full surface of one of the spaced members of the carrying frame, said arcuate bars supporting said container laterally of said pair of bars when the tray rests on one of the spaced members.

MORRIS B. SOLOMON.
